US00D974966S

(12) **United States Design Patent** (10) **Patent No.:** **US D974,966 S**
(45) **Date of Patent:** **** Jan. 10, 2023**

(54) **VEHICLE**

(71) Applicant: **Einride AB**, Stockholm (SE)

(72) Inventor: **Daniel Sjoholm**, Hoor (SE)

(73) Assignee: **EINRIDE AB**, Stockholm (SE)

(**) Term: **15 Years**

(21) Appl. No.: **29/805,726**

(22) Filed: **Aug. 30, 2021**

Related U.S. Application Data

(62) Division of application No. 29/718,861, filed on Dec. 30, 2019, now Pat. No. Des. 931,174, which is a division of application No. 29/621,033, filed on Oct. 4, 2017, now Pat. No. Des. 877,659.

(57) **CLAIM**

I claim the ornamental design for a vehicle, as shown and described.

DESCRIPTION

FIG. 1 is a perspective view of a first embodiment of a part of a vehicle;

FIG. 2 is a front plan view thereof;

FIG. 3 is a right side elevational view thereof;

FIG. 4 is a left side elevational view thereof;

FIG. 5 is a top plan view thereof;

FIG. 6 is a rear elevational view thereof; and

FIG. 7 is a bottom plan view thereof.

FIG. 8 is a perspective view of a second embodiment of a part of a vehicle;

FIG. 9 is a front plan view thereof;

FIG. 10 is a right side elevational view thereof;

FIG. 11 is a left side elevational view thereof;

FIG. 12 is a top plan view thereof;

FIG. 13 is a rear elevational view thereof; and,

FIG. 14 is a bottom plan view thereof.

Broken lines included in the figures show portions of the vehicle that form no part of the claimed design.

1 Claim, 8 Drawing Sheets
